No. 37,339.

Patented February 14, 1905.

UNITED STATES PATENT OFFICE.

OLIVE T. CUSHMAN, OF NEW YORK, N. Y.

DESIGN FOR A PLATE-SERVER.

SPECIFICATION forming part of Design No. 37,339, dated February 14, 1905.

Application filed January 23, 1905. Serial No. 242,436. Term of patent 14 years.

To all whom it may concern:

Be it known that I, OLIVE T. CUSHMAN, a citizen of the United States, residing at New York, in the county of New York and State of New York, have invented a certain new, original, and ornamental Design for Plate-Servers, of which the following is a specification, reference being had to the accompanying drawing, forming a part thereof.

10 The figure is a perspective view of a plate-server, showing my new design.

I claim as new and desire to secure by Letters Patent of the United States—

The ornamental design for a plate-server, as shown.

OLIVE T. CUSHMAN.
